Primary Examiner — Austin Murphy(74) *Attorney, Agent, or Firm* — Christensen O'Connor Johnson Kindness PLLC(57) **CLAIM**

The ornamental design for a coordinate input instrument, as shown and described.

DESCRIPTION

FIG. 1 is a front perspective view of a coordinate input instrument according to a representative embodiment of my new design;

FIG. 2 is a rear perspective view of the coordinate input instrument shown in FIG. 1;

FIG. 3 is a side view of the coordinate input instrument shown in FIG. 1, the side opposite of the side shown in FIG.

3 being a mirror image thereof and therefore not shown;

FIG. 4 is a front view of the coordinate input instrument shown in FIG. 1;

FIG. 5 is a rear view of the coordinate input instrument shown in FIG. 1;

FIG. 6 a top view of the coordinate input instrument shown in FIG. 1; and,

FIG. 7 is a bottom view of the coordinate input instrument shown in FIG. 1.

The broken lines show portions of the coordinate input instrument which form no part of the claimed design.
